UNITED STATES PATENT OFFICE

EDWARD J. HEALY, OF BALTIMORE, MARYLAND

RACE-STARTING GATE

Application filed December 5, 1929. Serial No. 411,908.

The present invention relates to race-starting gates, and particularly to gates having a plurality of spaced partitions forming stalls for the horses at the start of the race, and arranged to permit the removal of the partitions to clear the race track after the race has begun.

It is now considered desirable by the managers of race tracks that the horses be separated from each other by spaced partitions forming stalls while they are being aligned before the starting tape or other barrier. The partitions must be high enough and long enough to prevent a restive or unruly horse from kicking the horses in contiguous stalls. They must also be high enough to make it difficult for one jockey to interfere with another, or with the mount of another while waiting for the starting signal.

While it is agreed that stalls used in conjunction with a starting tape, save time in the positioning of the animals before the tape and have the advantages mentioned yet they have not been generally adopted. One serious disadvantage lies in that there is always the possibility of a restive horse unmounting and seriously injuring its jockey by brushing him against the wall of the stall when it swerves and plunges forward at the start of the race. Another disadvantage is that the confining walls of the stalls affect horses accustomed to starting on tracks free of such obstructions in training and in competition, and cause them to hesitate for a moment or become balky and unruly when the signal to start is given.

The principal object of my invention is to remove the disadvantages mentioned by providing a starting gate with partitions arranged to recede rearwardly and upwardly at a high speed so that they may practically disappear from the horses' line of vision simultaneously with the releasing of the starting tape, or with the sounding of the starting gong. My invention thus affords substantially "free field" starting conditions, and removes from the mind of the jockey the dread of being unmounted in starting.

On many race tracks the horses must pass the starting point several times in the course of a long race. Another important object of my invention is to provide a gate of which the partitions are swung above the track at starting so that it will not be necessary to remove the structure from the fairway when

the length of the race necessitates passing the starting point several times in the course of the race.

My invention contemplates the use of a portable structure that may be moved on rails to various points on the track. It contemplates a structure wide enough to support stalls capable of accommodating fifteen or more horses. When such a structure has to be moved, it will be obvious that, because of its inherent flexibility, there is the possibility of its being twisted and de-railed should the two ends of the structure not move in synchronism. It is a further object of my invention to provide means for assuring substantially synchronous movement of the two supporting end columns of the structure to prevent twisting and derailment. One of the possible embodiments of my invention is illustrated in the accompanying drawings, in which:

Figure 1 is an elevational view of my invention as seen from the rear, with parts broken.

Figure 2 is a wiring diagram of electric circuits employed.

Figure 3 is a side elevational view.

Figure 4 is a view of certain details with parts in section.

In the drawings, for convenience of illustration, I have limited the size of the gate to six stalls, but it will be understood that the gate may be lengthened and equipped with enough stalls to accommodate the usual number of horses starting in a race.

In the drawings, the numeral 10 indicates the supporting end columns of my starting gate. The columns 10 are suitably anchored for support on a carriage 11 on which flanged wheels 12 are suitably journaled for rotation, and the wheels roll on rails 13, laid along the race track, so that the gate may be moved to different starting positions on the track.

The two end columns are tied together by, and support, a beam 14, extending across the race track, and the beam 14 is supported against buckling by tie rods 15, secured to the beam and the end columns. Mounted on the beam 14 are bearing hangers 16 in which a shaft 17 is journaled for rotation. The ends of the shaft extend through the columns and are provided with arms 18 upon which counterweights 19 are secured. Stalls to accommodate the horses are formed of spaced rectangular frames or partitions 20 which de-

pend from the shaft 17 by the arms 21. The arms and the frames are padded to protect the jockeys and their mounts against injury through contact with the walls of the stalls, but for the sake of clearness in the drawings, padding has not been shown. A tape to aline the horses may be stretched across the front end of the stalls, and the horses may be walked into the stalls from the rear side of the gate.

As best shown in Figure 3, the weight of the frames 20 is counterbalanced by the weights 19 on the arm 18. The shaft 17 is restrained against movement by a dog 22 pivoted on the column 10, entering the teeth of a toothed wheel 23 mounted on the shaft 17. The dog 22 may be disengaged by movement of a connecting rod 25, and a link 26. To ensure quick movement of the shaft 17 and of its connected frames 20 when the dog 22 is disengaged, a spring 27 is connected to the arm 18 and the column 10, and it is in tension when the stalls are in the starting position. Upon the sounding of the starting gong, the race starter, by depressing lever 24, releases the shaft 17, and as the horses dart forward the frames 20 start rearwardly and upwardly to clear the track.

It will be readily perceived that the effective speed of the rearwardly moving stalls will be that considered with reference to a stationary object plus the speed of the forwardly moving horses. The rate at which the horizontal component of movement of the frame, i. e., the component in line with the body of the horse, diminishes because of the angular motion of the frame is also important. It will be obvious that the stalls, as confining means, practically disappear out of the sight of the jockeys and the horses simultaneously with the sounding of the starting gong. The men and animals, therefore, start off as though they were on a track clear of all obstructions.

The lever 24 and its connected rod 25 may be so associated with the starting gong and the alining tape that the depressing of the lever will simultaneously sound the gong, release the tape, and release the shaft 17.

While I have shown the arm 21 swung to the horizontal position after the horses have started, it will be obvious that I may readily alter the shape of the arm and of the frame, and the manner of mounting the counterbalancing weights, so that the frame may swing to lie transversely across the beam 14.

On the shorter race tracks, the horses must pass the starting point several times in the course of a long race. My invention provides means for swinging the stalls above the track so that the horses and riders may pass under them, and the track is cleared with no more effort than that necessary to depress the lever 24.

It is often desirable that the starting gate

be moved to several different positions along the race track. I have arranged my gate so that it may be readily moved on rails laid on both sides of the track. Because of the necessarily great length of the transversely extending beam 14 the whole structure is inherently flexible and subject to twisting and derailment should the carriages 11 and the columns 10 not advance in synchronism.

I will now describe my means for obtaining substantially synchronous movement of the two carriages 11. An electric motor 28, preferably of the series type, is suitably mounted on each of the carriages 11, and the motor is suitably connected by gearing to a toothed gear wheel 29 secured on the flanged wheel 12. The teeth of the gear wheel 29 mesh with the teeth of a toothed rack 30 secured to the rail 13.

The motors are connected in series, and receive energy from a storage battery 31, which may be suitably mounted on a platform 32 secured to the column 10. A controller 33, including the usual switch and rheostat means, is mounted on the platform 32 for controlling the motors. The arrangement described ensures substantially synchronous movement of the two carriages, particularly at starting when the inertia of the structure has to be overcome. I have shown but a relatively short length of toothed rack secured to the rail to ensure positive traction, without slip, while the structure is being accelerated, but it is obvious that the rack may be laid coextensive with the rails to ensure positive traction at all times.

The race starter may stand on the platform within easy reach of the shaft releasing lever 24; and the starting gong and the means for releasing the starting barrier may be conveniently located on the column 10.

It is well known that when a horse is being walked up to the stalls it is more manageable, less restless, than when it is compelled to wait in the stall for the starting signal. It will be obvious that my starting gate may be slowly advanced along the track so that the horses may be walked while in the stalls, and when the starter, who is carried along with the gate, finds that they are in alinement before the barrier, he can then simultaneously sound the gong, release the barrier, and release the stall partitions to move rearwardly and upwardly out of the line of vision of the horses. The horses will be in motion and under control when the gong is sounded, and false starts caused by rearing and kicking and side-plunging are avoided.

In order to enable the milling throng at the race course to readily determine the position of the stationary gate on the track, I have provided light signals 34 mounted on the column 10.

I am aware that many changes may be made and numerous details of construction

may be varied through a wide range without departing from the principles of this invention, and I, therefore, do not pur pose limit ing the patent granted hereon, other wise than

5 necessitated by the prior art.

What is claimed is:

1. A starting gate for race tracks, comprising means for separating the horses while they are in starting position on the 10 track, and means operable upon the start of the race for moving the said separating means out of position on the track in a direction out of the path of the horses' vision and to thereby leave the track unobstructed so that the 15 horses may re-pass through the gate in the course of a race.

2. A starting gate for race tracks comprising a member supported to extend transversely over the race track, a plurality of 20 spaced partitions mounted turnable on and depending from the member to accommodate horses in starting position on the track, and means arranged to impel the partitions in a direction opposite to that of the horses when 25 they are in motion in a race, and to leave the track unobstructed so that the horses may re-pass through the gate in the course of a race.

3. In a starting gate for race tracks including a shaft rotatably supported to extend transversely over the race track, a plurality of spaced partitions secured to the shaft for rotation therewith and depending therefrom to provide stalls to accommodate horses in starting position on the track, and 35 means arranged to rotate the shaft to impel the partitions in a direction opposite to that of the horses when they are in motion in a race.

4. In a starting gate for race tracks including a shaft rotatably supported to extend across the race track, a plurality of spaced partitions secured to the shaft for rotation therewith and depending therefrom to provide stalls to accommodate horses in 45 starting position on the track, a forwardly extending arm secured on the shaft, counter-weights mounted on the arm to rotate the shaft whereby to impel the said partitions rearwardly and upwardly, means to restrain 50 the said shaft against movement, and means to release the said restraining means.

5. In a starting gate for race tracks including a shaft rotatably supported to extend across the race track, a plurality of spaced partitions secured to the shaft for rotation therewith and depending therefrom to provide stalls to accommodate horses in the starting position on the track, a forwardly extending arm secured on the shaft, tensioned spring means in operative association 55 with the arm to impel the arm downwardly and so rotate the shaft whereby to impel the

said partitions rearwardly and upwardly, means to restrain the shaft against rotation, and means to release the said restraining means.

6. In a starting gate for race tracks, including a revolvable shaft supported to extend across the track, a plurality of rearwardly extending partitions secured to the shaft for rotation therewith and depending from the shaft to provide stalls to accommodate horses in the starting position on the track, a forwardly extending arm secured to the shaft, counterweights mounted on the arm, a toothed member secured on the shaft, a pivoted dog adapted to enter the teeth in the toothed member to restrain the shaft against rotation, and means adapted to disengage the dog.

7. In a starting gate for race tracks, rails positioned on both sides of the track, a starting gate mounted for movement on the rails and including spaced upwardly extending means supporting a rotatable shaft extending across the track, a plurality of spaced partitions secured to the shaft for rotation therewith and depending from the shaft to provide stalls to accommodate horses in the starting position on the track, power means on the gate arranged to impart motion to the gate along the rails, and means arranged to rotate the shaft to impel the said partitions in a direction opposite to that in which the horses move in the course of a race.

8. In a starting gate for race tracks, means for separating horses while they are being alined in starting position on the track, the said means being arranged for forward motion on the track while the horses are being alined, and means operable at the start of the race for moving the said separating means rearwardly and upwardly to leave the track unobstructed so that the horses may re-pass the starting point in the course of a race.

9. A starting gate for tracks comprising, a member adapted to extend transversely across the track, means swingably mounted on said member for separating horses while they are being alined in starting position on the track, the said member and the said swingable separating means being arranged for forward motion with the horses while they are being alined, and means arranged to impart sudden rearward and upward movement to said swingable means with respect to movement of said member at the start of the race to leave the track unobstructed so that the horses may re-pass through the gate in the course of the race.

In testimony whereof I hereunto affix my signature.

EDWARD J. HEALY.
